UNITED STATES PATENT OFFICE.

WILLIAM ELBERT SEXTON, OF BALTIMORE, MARYLAND, ASSIGNOR, BY MESNE ASSIGNMENTS, TO THE BALTIMORE TRUST COMPANY, TRUSTEE, A CORPORATION OF MARYLAND.

GAS RANGE.

Application filed April 11, 1924. Serial No. 705,766.

To all whom it may concern:

Be it known that I, WILLIAM ELBERT SEXTON, a citizen of the United States, residing at Baltimore, in the State of Maryland, have invented certain new and useful Improvements in Gas Ranges, of which the following is a specification.

This invention relates to improvements in gas ranges and is more particularly directed to ranges for use in hotels, restaurants and large institutions where it is common to employ a battery of ranges.

An object of the invention is to provide an improved construction and arrangement of burner-piping, manifold and distributing piping for supplying gas to the various burners, or to groups or sets of burners and to so arrange the piping that a single range or a battery of ranges may be supplied with 20 a single supply-pipe.

Another object of the invention is to provide an improved group-arrangement of burners and to connect the burners in a group with the gas-supply so that all the 25 burners of a group or only a portion thereof as desired may be operated through the medium of a single valve.

A further object of the invention is to provide an improved construction of gas-supply main.

With these, and other objects in view, the invention is illustrated in the accompanying drawings, wherein,—

Fig. 1 shows a range in front elevation to 35 which the improved arrangement of burners, supply-pipe and branch pipes are attached.

Fig. 2 illustrates a horizontal sectional detail across the top of the range and above 40 the burners,—the section being taken on the line 2—2 of Fig. 1.

Fig. 3 shows an enlarged sectional elevation of the main and burner-branch pipes together with the valve devices therein 45 whereby gas may be supplied to all the burners of a group or to some only of the burners of said group through the operation of a single valve.

Fig. 4 illustrates a vertical sectional detail 50 through the upper front portion of the range, the gas-supply main, the branch control-valve and the branch pipe to a group of burners,—the section being taken on the line 4—4 of Fig. 3.

Fig. 5 shows a cross-sectional detail 55 through the branch-burner pipe at one of the burner nipples, as the same would appear if viewed on the line 5—5 of Fig. 3.

Fig. 6 illustrates another sectional detail adjacent to the upper pilot-burner, as the 60 same would appear if viewed on the line 6—6 of Fig. 3.

Fig. 7 shows on a reduced scale and in side view, the upper portion of the range and the piping at the front thereof and 65 the relation of said piping with respect to the top of the range.

Fig. 8 illustrates a sectional view through one of the branch burner valves showing 70 the same in position to feed gas to one passage only of the branch.

Fig. 9 shows a similar view of the valve when the latter is in the cut-off position.

Fig. 10 illustrates a front view of the lower burner-supporting plates. 75

Fig. 11 shows a vertical sectional detail through the front and rear burner-supporting means, as the same would appear if viewed on the line 11—11 of Fig. 10.

Fig. 12 illustrates a vertical sectional detail of the lower burner-supporting plates 80 as the same would appear if viewed on the line 12—12 of Fig. 10, and

Fig. 13 shows a horizontal sectional detail through said lower burner-supporting plates,—the section being taken on the line 85 13—13 of Fig. 10.

Referring to the drawings the numeral 12, designates a front plate of the range 90 which latter has an upper burner compartment 13; a lower burner compartment 14, and an oven between the said upper and lower compartments.

A door 15, having novel features of construction and operation, but forming the 95 subject of a separate application, is pivotally sustained at 16, in suitable bracket-plates 17 whereby the same may be swung outwardly and downwardly. Novel door latch, guide and supporting devices 18, 19 and 20 respectively also form features of 100 said separate application and therefore are not described herein.

The upper burner compartment 13 is 105 located directly beneath the range-top 21 and immediately over the oven, and in this compartment I provide a central horizontal pilot burner 22; a group of heating-burners

23 being arranged on one side of said pilot-burner and another group of heating burners 24 is located at the opposite side of said pilot-burner as best illustrated in Figs. 1, 2 and 3 of the drawings.

In practice, it is frequently desirable to provide a battery or a plurality of ranges in a row, and it is also desirable that the fuel-gas be supplied so as to avoid a multiplicity of pipes and in such a way that an entire group of burners or only certain burners of such group may be used or not as desired.

It is therefore an object of the present invention to provide a novel arrangement of burners and gas-supply pipes, branches and valves, whereby fuel gas may be supplied to a set or group of burners, or to certain burners of a group of burners by means of 20 a single control valve and without unnecessary use of burners.

With these objects in view, I provide a horizontal upper main pipe 26, a lower horizontal main pipe 27 and a vertical pipe 25 25 which connects said upper and lower main pipes.

This vertical pipe 25 is preferably provided with a valve 10 by means of which gas to the lower main 27 may be cut off 30 without interrupting the passage of gas through the upper main.

The upper main 26 extends horizontally across the front of the range from one vertical side edge to the other of the range, 35 and said upper main is provided with a lateral flange 11 at its upper inner side which flange extends toward and is flush with the top 21 of the range and seats closely against the rim-edge of and around 40 said range-top. By thus seating the flange 11 of the upper main against the rim edge of the range-top I avoid the formation of a vertical space between said upper main and the said range-top into which space 45 grease and food materials would collect.

Each upper main 26 is provided on its under side, and midway between its ends, with so-called pads 29 and 30 respectively,—the pad 29 being located between two pads 50 30, and each of the pads 30 has a port extending downwardly therethrough for the passage of gas from the main as will presently be more clearly explained.

To the under side of one pad 30, there is 55 attached one end of a branch pipe 31 while a similar branch pipe 32 is attached to the underside of the other pad 30.

The two branch pipes 31 and 32 extend 60 downwardly from the respective pads 30 and one of these pipes 31 is turned laterally in one direction while the other pipe 32 extends laterally in an opposite direction. Both of these branch pipes however are located directly beneath the upper main 26, and extend in opposite directions across the

upper front portion of the range, as clearly shown in Fig. 1 of the drawing.

The branch pipes 31 and 32 are both of novel construction and the pipe 31 is provided with a specially-constructed valve 33 70 while the pipe 32 has a similar constructed special valve 34 which valves are interposed between and control the passage of gas from the upper main 26 to said branch pipes.

It is important to note that the branch 75 pipes 31 and 32, which are of like construction, are interiorly divided by a longitudinally-extending partition 35 whereby to produce two longitudinal chambers or passages 80 36 and 37 respectively in each of those 85 pipes, as may clearly be seen in Fig. 3, 4 and 5 of the drawings.

The outer ends of the branch pipes 31—32 are supported in brackets 28 which latter 90 also sustain the upper main, and said outer branch pipe-ends are closed in any suitable manner and the longitudinal chambers or 95 passages 36—37 are entirely separate and independent and have no communication one with the other.

The inner ends of these branch burner-pipes 31—32, are bolted or otherwise secured up against the respective pads 30 on the under side of the main 26, and adjacent to this point of attachment each pipe (31—32) 95 has a valve-seat 38 against which latter the valves 33 or 34 seat.

In the present instance the valve seats 38 in said pipes have the form of tapered 100 passages while the valves 33 and 34 are of the tapered plug-valve type, and each valve-seat is provided with a port 39 that communicates with the port 40 in the pad 30 of the main 26 and each seat also has two ports 41 and 42.

The valve-seat port 41, (see Figs. 3, 8 and 9) opens into the longitudinal chamber or passage 36 is the branch burner-pipe 31 or 32 while the valve-seat port 42 opens into the longitudinal chamber or passage 37 in 110 said branch burner-pipe.

It is therefore to be understood that valve port 41 is located at one side of longitudinal partition 35 while port 42 is on the opposite side of said partition.

The valves 33 and 34, which are of like construction, each have a port 43, to coact with port 39 in the valve-seat and said valves also have ports 44 and 45 to coact with the ports 41 and 42 that open into the chambers or passages 36 and 37.

The valves 33 and 34 are obviously capable of being rotated or turned in the seats 38 and, as shown in Fig. 3, when the valve is in one position gas from the main 26 may pass through ports 40, 39, 43, 44 and 45, and through ports 41 and 42 to both chambers 36 and 37 in the branch burner-pipe; that when said valves 33 or 34 are turned to the position shown in Fig. 8 gas 125 130

from the main will pass through ports 40, 39, 43 and 44 and then through port 42 to one chamber or passage 37 in the branch burner-pipe. In this latter position (Fig. 8) it will be noted that no gas can pass through the valve to port 41 and chamber or passage 36 in the branch pipe so that the latter position of the valve will cut off the gas to one passage or chamber 36 while gas may flow to the other passage or chamber 37.

By reference to Fig. 9 of the drawing it will be noted that the valve 33 is shown turned to a position where no gas can pass from the main through port 39 and also that both ports 41 and 42 to the passages 36 and 37 of the branch burner-pipe are cut off from the gas supply.

The object in providing the two passages 36 and 37 and the valve 33 or 34 that will control the flow of gas to one or both or to neither of said passages 36 or 37 is so that, through the operation of a single valve, certain burners of a group of burners may be cut off while one or more burners of the same group may be supplied with gas and allowed to burn.

The burners under the range-top are arranged in groups 23 and 24,—there being in this instance four burners in each group although the number may obviously be varied.

The burners, say burners 23 of the one group, are connected to the branch-pipe 31 so that some of the burners of the group will communicate with passage 36 of said pipe 31 while other burners of the same group will communicate with the passage 37 in said pipe 31.

The manner of connecting the several burners of a group with the branch-pipe 31 is illustrated in Figs. 3, 4 and 5 of the drawings and to distinguish certain of these burners from others of the same group in these particular views of the drawing, I have designed two of them 23^a and the other two are designated 23^b.

By reference therefore to said Figs. 3, 4 and 5 it will be noted that the burners 23^a of the group 23 are connected to pipe 31 so as to communicate with the passage 36,—the connection being by means of the ports 46, and the burners 23^b are connected to the passage 37 of the pipe 31 through the ports 47.

In this way some of the burners of group 23 are supplied with gas from passage 36 of the branch-pipe 31 while other burners of the same group are supplied with gas from passage 37 of said branch-pipe 31, and the supply of gas to one or both of these passages is controlled by the valve 33, hence, in the operation of the valve, two burners only (in the present instance) or all the burners in the group of burners 23, may be supplied with gas.

By means of this construction, the one valve and the one branch pipe 31 will permit all four burners in the group to be operated until the range-top is sufficiently hot and then a manipulation of the valve 33 will operate to cut off gas from two of those four burners but allow the other two burners to continue operation.

To facilitate the operation of the valves 33 and 34, each of them is provided with an indicator or pointer 48 to show the number of burners in operation when the valve is in a given position.

The central pilot burner 22 at the top of the range is supplied with gas from the main 26 through a valve 49, and as the supply is usually maintained as long as any part of the range is in operation this pilot burner will always be in readiness to ignite the gas turned on through either group of burners 23 or 24.

Each end of the upper main 26 on a range is provided with a flange 50 (see Fig. 7) having perforations 51 therein so that said flange may be coupled with a like flange on the main of another range and thus produce a continuous main where two, three or more ranges are coupled together in a battery. The main at the end of such a battery will have a plate attached to its flange 50 whereby to effectually seal that end.

The lower horizontal main 27, extends from the vertical supply-main 25, across the front of the range and is sustained in suitable brackets 52, that project from the plates 17. This lower main has position in a horizontal plane just in front of the lower burner compartment 14 where a series of oven burners 53 are located.

The front wall 12 of the range is provided with a plurality of openings 54 through which the burners may readily be inserted so that the inner ends thereof may be inserted in suitable sockets 55 at the rear as shown in Fig. 11 of the drawing. The forward or outer ends 56 of the burners are flared or of a bell shape and the openings 54, in the front plate 12 of the range are larger than said flared ends of the burners to permit ready manipulation of the latter when the same are being connected to or disconnected from the nipples 57 that project from the main 27 and through which gas is supplied.

To provide a proper support for the outer ends of these oven burners and also to effect a closure of the large openings 54 in the front plate 12 of the range, I provide two horizontal plates 58 and 59 respectively of a novel construction.

By reference to Figs. 1, 10, 11, 12 and 13 of the drawings it will be noted that these plates 58—59 have rabbeted horizontal edges 60, which lap and interlock, and that at in-

- tervals said edges are provided with segmental notches 61 which are beveled. When these plates are brought together the notches in the edge of the one plate will register with 5 the notches in the edge of the other and the registered notches will together form circular openings with a beveled wall so as to close about the flared end 56 of the burner and retain the latter in place.
- 10 The opposite ends of the plates 58 and 59 are outwardly flanged so as to project over and seat close against the vertical edge of the bracket plates 17 and screws 62, rigidly hold the plates in position.
- 15 The edges 60 of the plates 58 and 59 are also provided with semi-circular notches 63, so that the nipple 64 of a pilot burner may pass therethrough adjacent to or between two of the oven burners 56.
- 20 The nipples 57 of the oven burners and the nipple 64 of the pilot burner are each connected to the lower horizontal main 27, and each of these nipples has its own control valve such as indicated at 65 in Fig. 1.
- 25 The lower main 27, of one range like the upper one 26, is intended to be coupled to a like lower main on the next range in a battery of ranges, or be closed by a blank plate as desired.
- 30 From the foregoing explanation it will be understood that the control valves 33, 34 and 49 to the upper group of top burners are closely located at the center of the range where they are readily accessible to turn on or off as desired and that the gas to the two groups of top burners flows from the upper main into the branch pipes and to one or both passages 36 and 37 as desired.
- 35 It will also be understood that the supply of gas to the lower oven burners is taken from the lower main directly to the burners themselves but is controlled by separate valves so that any one or more of said lower burners may be utilized at a time.
- 40 Having described my invention, I claim,—
1. In a gas range the combination with a plurality of top burners arranged in groups, of a plurality of bottom burners, a lower main for supplying gas to the lower burners, an upper main, a pipe connecting said lower and upper mains and maintaining communication between the two, a branch from the upper main to one group of top burners a separate branch from the upper main to 50 another group of top burners, said branches being independent of the pipe that connects the lower and upper mains, and separate valves between the upper main and said branches for controlling the flow of gas from said upper main to said branches.
- 55 2. A gas range having a cooking top in combination with a gas main extending across the front of the range, a plurality of gas burners beneath the top and said burners being arranged in groups, a branch pipe for 55 each group of burners and each branch having a connection with the main and all of the burners of a group being connected to the one branch pipe that supplies gas to that particular group of burners, the connections between the several burners of a group and the branch-pipe for that group being valveless,—said branch pipe having means with a single valve coacting with that means to pass gas from the branch to a plurality 70 of the burners of the said group while cutting off the flow of gas from the same branch pipe to the other burners of the same group.
3. A gas range having a cooking top in combination with groups of burners beneath 80 said top, of a gas-supply main extending across the front of the range in a plane above said burners, a branch pipe connecting one group of said burners with the said main, another branch pipe connecting another 85 group of burners with said main, a separate valve in each of said branch pipes and means in each of said branch pipes and controlled by the one separate valve therein for cutting off the passage of gas to some 90 burners of a group but allowing gas to flow to other burners of the same group.
4. A gas range having a cooking top in combination with groups of burners beneath 95 said top, said groups of burners being arranged at opposite sides of the vertical center of the range front, of a gas supply main extending across the front of the range immediately below the top, two oppositely-extending branch pipes connected with the 100 main and each extending to a different group of top burners,—each branch pipe having a plurality of passages therein and the passages communicating with different burners in the group of burners which that branch supplies with gas and valve means in each branch pipe to control the flow of gas through the plurality of passages therein.
5. A gas range having a cooking top in 110 combination with groups of burners beneath said top, of a gas supply-main extending across the top of the range-front, a pilot burner connected centrally to the main, two branch pipes having connection with the 115 main adjacent to and at opposite sides of said central pilot-burner connection,—one branch pipe extending horizontally in one direction from the pilot burner and the other branch pipe extending horizontally in 120 an opposite direction from said central pilot burner and the outer ends of said two branch pipes near the sides of the range being permanently closed, and each branch pipe passing and having connection with a group of 125 top burners.
6. A gas range having a cooking top in combination with groups of burners beneath said top, of a gas supply-main extending across the top and front of the range, a cen- 130

tral pilot burner connected to the main, two branch pipes each having connection with the main adjacent to and at opposite sides of said pilot-burner connection,—one branch
5 pipe extending horizontally in one direction from the central pilot burner and the other branch pipe extending horizontally in an opposite direction from said central pilot burner and the outer ends of said two
10 branch pipes terminating adjacent to the vertical sides of the range and being permanently closed, connections between one branch pipe and one group of burners and a valve at one end of each branch pipe adjacent
15 to the pilot burner for controlling the flow of gas from the main into its branch. 45

7. A gas range having a cooking top in combination with a group of burners beneath the top, of a gas main, a branch pipe
20 leading from the main past the burners of the group, said branch pipe having a plurality of passages therein, connections between one passage of the branch and some of the burners of the group, connections between another passage of the branch and another burner of the same group and a single valve in the branch to control the flow
25 of gas through the plural passages therein. 50

8. A gas range having a cooking top in

combination with a group of burners beneath the top, of a gas main, a branch pipe leading from the main and extending past the burners of the group, said branch pipe having a partition therein which forms a plurality of separated interior passages in the branch pipe, connections between a passage at one side of the partition and some of the burners of the group of burners, connections between a passage at another side of the partition and another burner of the said group and a single valve in the branch between the main and the plural passages in the branch, said valve having ports to connect the main with one or more of the branch passages. 40 45

9. A gas range having a front and a cooking top in combination with burners beneath said top, of spaced brackets on the front of the range, a gas main extending horizontally across the front of the range and supported by said brackets, said main having a rearwardly-extending top flange to seat close against said range-front and top to prevent the formation of a space between the main and range-front and a branch pipe connecting the main with the burners. 50 55

In testimony whereof I affix my signature.
WILLIAM ELBERT SEXTON.
